(57) CLAIM

The ornamental design for a mounting assembly for an article holder, as shown and described.

DESCRIPTION

FIG. 1 is a perspective view taken from one corner of a mounting assembly for an article holder, and showing the mounting assembly supporting an article holder, said article holder being shown in phantom and not claimed herein; FIG. 2, an exploded view taken from the bottom and one corner;

FIG. 3, a perspective view of the mounting assembly, taken from a corner;

FIG. 4, a similar perspective view, taken from above the corner;

FIG. 5, a top plan view;

FIG. 6, a side elevation view;

FIG. 7, a bottom plan view;

FIG. 8, a right end elevation view; and,

FIG. 9, a left side elevation view.
